UNITED STATES PATENT OFFICE

2,036,798

HYDRAULIC OPERATOR

Theodore W. Driesch, Schenectady, N. Y., assignor to General Electric Company, a corporation of New York

Application June 12, 1934, Serial No. 730,238

3 Claims. (Cl. 60—52)

This invention relates to hydraulic operating mechanism, more particularly to hydraulic operating mechanism in which an electric motor driven impeller pump immersed in a fluid container is utilized to produce a differential in fluid pressure on opposite sides of a piston to effect movement thereof, and it has for an object the provision of a simple, reliable and improved device of this character.

10 More specifically this invention relates to hydraulic operating mechanism in which the electric motor is mounted above the surface of the fluid and the impeller pump is rotated by means of a shaft connecting the motor and the impeller, and a more specific object of the invention is the provision of means for preventing the introduction of air into the impeller due to rotation of the shaft. An additional object is the provision of means for cushioning the end of the 20 return stroke of the piston, thereby to eliminate undesirable shocks and stresses. This invention is an improvement of the hydraulic operating mechanism disclosed in U. S. Patent No. 1,993,613 to Walter O. Lum, filed December 19, 1929 and assigned to the assignee of the present invention.

In carrying this invention into effect in one form thereof a piston is movably mounted in a fluid container, and the impeller is located within the fluid container beneath the surface of the fluid. The pump impeller drive shaft extends above the surface of the liquid to an electric driving motor and a cover pipe is provided which surrounds the impeller shaft and extends from a point at or near the surface of the fluid to a point a substantial distance beneath the surface.

The pump housing is provided with intake and exhaust passages which communicate respectively with fluid on opposite sides of the piston, and means actuated by the piston, near the extremity of its return stroke, are provided for gradually throttling the exhaust passage and thereby decreasing the rate of the return flow of fluid so as to cushion the termination of the piston stroke.

For a better and more complete understanding of the invention, reference should now be had to the following specification and to the accompanying drawing in which Fig. 1 is an elevation partly in section and with parts broken away, and Fig. 2 is a broken view in elevation partly in section illustrating an operating condition of the cushioning means.

55 Referring now to the drawing, a cylindrical

fluid container 10 is provided with a cover plate 11 upon which an electric driving motor 12 is vertically mounted. The cover plate 11 is constructed to provide an integral supporting platform 13 beneath the top of the container 10.

The cylindrical casing 10 is filled with a suitable fluid medium, such for example as oil, to a point substantially level with the platform 13. A piston 14 is arranged within the cylindrical casing 10 for vertical movement, which is transmitted to an external load by means of a pair of connecting rods 15. The lower ends of these connecting rods 15 are secured by suitable fastening means 16 to the piston 14 whilst the upper ends of these connecting rods extend through the cover plate 11 and are secured to a cross-head 17 which is adapted to be connected to a suitable load. At the bottom of the container is an impeller pump illustrated as comprising a housing 18 within which an impeller 19 is rotatably mounted. The housing 18 is provided with suitable centrally disposed intake passages 20 together with a plurality of exhaust ports 21 arranged circularly in the housing 18. Due to the section taken in Fig. 1 of the drawing, only 25 a single exhaust port 21 is clearly visible.

As shown, the housing member 18 is secured by a suitable fastening means to the lower extremity of a tubular member 22 the upper extremity of which is suitably secured to the supporting platform 13. Openings 23 are provided in the wall of the tubular member 22, thus providing communication from the space above the piston 14 to the intake passages 20 of the pump. It will also be clear that the walls of the tubular member 22 serve as a partition means between the intake passages 20 and exhaust ports 21 and thus restrict the discharge of the pump to the space beneath the piston.

A vertical drive shaft 24 is rotatably mounted in a bearing 25 in platform 13 and in a bearing 26 which is centrally mounted in the pump housing 18. This drive shaft 24 is connected to the motor shaft 27 by suitable coupling means 28 so that rotation of the motor effects rotation 45 of the pump impeller 19. In order to prevent the formation of a vortex in the fluid with the resultant introduction of air into the pump impeller due to rotation of the shaft 24, a cover pipe 29 is provided which surrounds the drive shaft 24 and extends from a point at or near the surface of the fluid to a point a substantial distance beneath the surface. The inside diameter of the cover pipe 29 is slightly greater than the outside diameter of the shaft 24 so as 55

to provide a slight clearance and thus prevent actual contact. At its upper extremity, the cover pipe 29 is provided with a flange 30 which is secured by suitable fastening means to the 5 platform member 13.

In hydraulic operating mechanisms heretofore constructed, means have been provided for cushioning the return stroke of the piston upon de-energization of the pump driving motor for the 10 purpose of preventing the swiftly descending piston from striking its stop with a heavy hammer blow and setting up undesirable shocks and stresses in the mechanism. These means have left something to be desired with respect to controlling or varying the cushioning action during 15 the descent of the piston. In order to cushion the return stroke of the piston and to eliminate these undesirable shocks and stresses, a baffle plate 31 is provided for controlling the return 20 flow of the fluid from beneath the piston through the pump to the space above the piston. As shown, this baffle plate is in the form of a flattened ring surrounding the central intake of the pump housing and covering the circular row 25 of exhaust ports 21. When the pump is at rest, the baffle plate 31 is seated snugly against the pump housing so as to cover up the exhaust ports and cut off communication between the pump chamber and the space beneath the piston. 30 Holes are provided in the baffle plate through which studs 32 project and screw into the housing 18. Sufficient clearance is allowed between the head of the stud and the baffle plate to allow the latter to rise on these studs and uncover 35 the exhaust ports when a fluid pressure is established by rotation of the pump impeller.

Aligned holes are provided in the piston 14 and in the baffle plate 31 through which projects an adjusting rod 33. The upper extremity of this rod extends through the tank cover plate 40 11 and is provided with suitable thumb adjusting and lock nuts 34. A helical spring 35 surrounds the rod 33 and is arranged between the piston 14 and the baffle plate 31. A similar spring 36 is arranged between the lock nuts 37 45 at the lower extremity of the rod and the lower surface of the baffle plate 31. When the mechanism is in the deenergized condition in which it is illustrated in Fig. 1, the weight of the piston 14 compresses the spring 35, and this compressional force in turn compresses the spring 36.

With the above understanding of the elements and their organization in the completed device, the operation of the device itself will readily be understood from the following description:

Energization of the motor by connection with a source of electric power produces rotation of the drive shaft 24 and pump impeller 19. Fluid is directed into the intake passages 20 of the pump impeller by means of the tubular member 60 22. This fluid is drawn into the centrally disposed intake passages 38 and 39 in the impeller chamber. The impeller forces the fluid in a radial direction through the exhaust passages 21 as a result of which, a fluid pressure is produced against the lower surface of the baffle plate 31 of sufficient magnitude to cause the baffle plate to rise or tilt on the studs 32 and uncover the exhaust ports. Fluid is thus discharged from the impeller pump to the space beneath the piston 14 thus producing a pressure differential across the piston, i. e., a difference in fluid pressure on opposite sides of the piston. This causes the piston to move in an upward direction and this pressure and movement are

transmitted through the connecting rods 15 to the external load to which the cross-head 17 is connected.

As heretofore constructed without a cover pipe surrounding the drive shaft 24, a vortex in the fluid was formed by rotation of the shaft at high speed. The apex of this vortex followed downwardly along the shaft until it reached a point at which air was admitted into the intake of the impeller pump. This proved to be very undesirable because the presence of air gradually reduced the fluid pressure and increased the time required for lifting the load. The provision of the cover pipe 29 surrounding the drive shaft 24 and extending from a point at or near the surface of the liquid to a point several inches beneath the surface effectively prevents the formation of a vortex (which always begins to form at the surface) and prevents any air being drawn into the pump impeller. As a result, a maximum fluid pressure differential is produced and this increased pressure decreases the time required for lifting the load. In other words, the maximum lifting capacity of the device is substantially increased.

As the piston rises in the cylindrical container the compression on the springs 35 and 36 is gradually released until the piston 14 finally moves out of contact with the spring 35 entirely. At this time, the spring 35 is fully released but the spring 36 is still under sufficient compression to maintain the baffle plate 31 in its open position even though the fluid pressure against the lower surface of the baffle plate should disappear.

As long as the motor 12 is maintained energized, driving the pump impeller 19, the differential fluid pressure across the piston 14 is maintained. When the piston reaches the end of its upper stroke this pressure is still maintained and is not increased due to the fact that the pump is not a positive displacement pump.

Deenergization of the motor 12 stops the pump and the differential fluid pressure across the piston 14 disappears; as a result the piston descends under the attraction of gravity forcing the fluid back through the discharge opening in the pump housing and thence out through the intake opening and the tubular member 22 to the space above the piston. During this time, the baffle plate 31 is maintained in its raised position by means of the spring 36 as clearly illustrated in Fig. 2 of the drawing. This allows unrestricted return flow of fluid and the descent of the piston continues at a rapid rate until the piston strikes the upper extremity of the released spring 35. As the piston engages the spring 35, the latter is gradually compressed and gradually overcomes the pressure of the spring 36 thereby forcing baffle plate 31 slowly toward its seat. This gradually reduces the return flow of the fluid from the space beneath the piston to the space above the piston. Since the flow of fluid controls the speed at which the piston returns, it is clear that the piston must slow down. Continued descent of the piston continues to force the baffle plate downwardly thereby throttling the passageway and the return flow of fluid until the baffle plate is finally seated against the pump housing and completely covers the exhaust ports. This seating of the baffle plate occurs at the instant the piston reaches the end of its return stroke. By turning the adjusting rod 33, the tension of the spring 36 may be adjusted to obtain an absolutely smooth setting of the piston for any given

load and amount of travel. Thus, blows and stresses due to rapid descent of the piston are entirely eliminated.

Although in accordance with the provision of the patent statutes, this invention is described as embodied in concrete form, it will be understood that the elements and arrangements shown and described are merely illustrative and that the invention is not limited thereto since alterations and modifications will readily suggest themselves to persons skilled in the art without departing from the spirit of this invention or from the scope of the annexed claims.

What I claim as new and desire to secure by Letters Patent of the United States is:

1. An hydraulic operating mechanism comprising a liquid container, a piston movably mounted therein, an impeller pump immersed in said liquid and provided with an intake communicating with the liquid on one side of said piston and with an exhaust communicating with the opposite side of said piston, an electric motor for driving said pump thereby to effect transfer of liquid from one side of said piston to the opposite side thereof and produce a differential in the liquid pressure on opposite sides of said piston to effect movement thereof, a plate member covering said exhaust and arranged to uncover said exhaust when said impeller is energized and means actuated by the return stroke of said piston for gradually moving said member to close said exhaust gradually at the end of said return stroke thereby gradually to throttle the return flow of said fluid and to cushion the return stroke of said piston.

2. An hydraulic operating mechanism comprising a fluid container, a piston movably mounted therein, a pump immersed in the fluid comprising a pump housing provided with intake and exhaust openings and an impeller rotatably mounted therein, means affording communication from the fluid on one side of said piston to said intake and from the fluid on the opposite

side of said piston to said exhaust, an electric motor for driving said pump to produce a differential in the fluid pressure on opposite sides of said piston thereby to produce a working stroke of said piston, a baffle plate seated to cover said exhaust and responsive to energization of said pump to uncover said exhaust, and spring means connected to said plate and arranged to be engaged by said piston near the end of the return stroke thereof for gradually seating said plate and throttling said exhaust thereby to cushion the termination of said return stroke.

3. An hydraulic operating mechanism comprising a fluid container, a piston movably mounted therein, a pump immersed in the fluid comprising a housing provided with a centrally disposed intake port and a plurality of exhaust ports arranged in a circle surrounding said intake port and having an impeller rotatably mounted in said housing, partition means comprising a tubular member affording communication from the fluid on one side of said piston to said intake and from said exhaust to the fluid on the opposite side of said piston, a drive shaft extending into said fluid and connected to said impeller, an electric motor connected to drive said shaft to produce a differential in the fluid pressure on opposite sides of said piston to effect a working stroke thereof, a ring shaped baffle plate seated to cover said exhaust ports and responsive to energization of said pump for uncovering said ports, a rod projecting through said piston and baffle plate, spring means on said rod engaging said baffle plate arranged to be engaged by said piston on the return stroke thereof for gradually seating said baffle plate and throttling the return flow of fluid when said pump is deenergized, and a cover on said shaft for preventing the introduction of air into said pump due to rotation of said shaft.

THEODORE W. DRIESCH.
